(57) **CLAIM**

The ornamental design for the inspection and measurement device, as shown and described.

DESCRIPTION

The file of this patent contains at least one drawing executed in color. Copies of this patent with color drawings are available from the Office.

FIG. 1 is a bottom-front perspective view of an inspection and measurement device according to the design;

FIG. 2 is a front side elevation view thereof;

FIG. 3 is a back side elevation view thereof;

FIG. 4 is a right side elevation view thereof, a left side elevation being identical thereto; and,

FIG. 5 is a bottom plan view, a top plan view being identical thereto.

The portions of the article shown in broken line, including text in short dashed broken line, form no part of the claimed design.

The diagonal shading indicates a transparent appearance.
